UNITED STATES PATENT OFFICE.

HARVEY N. DAVIS, OF CAMBRIDGE, MASSACHUSETTS, ASSIGNOR TO RESEARCH CORPORATION, OF NEW YORK, N. Y., A CORPORATION OF NEW YORK.

INTERCHANGER TURBINE.

1,420,626.

Specification of Letters Patent. Patented June 27, 1922.

Application filed July 7, 1920. Serial No. 394,546.

To all whom it may concern:

Be it known that I, HARVEY N. DAVIS, a citizen of the United States, residing at Cambridge, in the county of Middlesex and 5 State of Massachusetts, have invented certain new and useful Improvements in Interchanger Turbines, of which the following is a specification.

This invention relates to apparatus for 10 cooling air or other gaseous mixtures so as to condition them for liquefaction, or for separation by rectification or both.

One of the objects of the invention is to increase the effectiveness of processes and 15 apparatus such as referred to.

Another object is to simplify apparatus of the character involved and lessen the cost of construction and operation thereof.

The invention will be fully explained with 20 reference to the accompanying drawings in which—

Fig. 1 is a diagrammatic representation of one of the many possible dispositions and 25 arrangements of apparatus embodying the invention; and

Fig. 2 is a diagrammatic representation of a part of the apparatus shown in Fig. 1.

The invention relates to those portions of air-liquefaction or distilling apparatus which 30 are commonly called fore-coolers, heat-exchangers or interchangers and to those associated devices which are commonly called expansion engines, and more particularly to an interchanger and a plurality of expansion engines arranged in accordance 35 with the principles fully set forth in my co-pending application Ser. No. 376,408 dated Apr. 24, 1920.

An interchanger of the type there de- 40 scribed includes, as a rule, a plurality of passages for passing one or more streams of previously cooled fluid in counter-current heat-exchanging relation with a stream or streams of fluid to be cooled.

In the above mentioned application it was 45 explained that the operation of such an interchanger will be most effective only if all the streams to be cooled have together at each level in the interchanger substantially 50 the same effective heat capacity as that of all cooling streams, together, at the same level, and that this can best be accomplished by withdrawing from one of the streams to be cooled at a plurality of different levels, 55 a plurality of streams each of which is

cooled by expanding with the performance of external work, and returned to an appropriate passage in the apparatus at a point where the temperature is substantially that of the expanded stream. 60

In the drawing 1 represents a channel or passage in an interchanger into the warmer end of which there passes a stream of air or other gaseous mixture that it is desired to cool, the said stream being under pres- 65

The present invention hinges on the fact that if the pressure in passage 1 is sufficiently high, and if the expansion engines are sufficiently efficient, not only the coldest 70 expansion engine, but also one or more of those next warmer in the series will produce in their respective streams drops in temperature so great that the exhausted gases will be partly liquefied, or at least 75 cooled substantially to the liquefaction point. The various streams exhausted from these engines will not, then, differ materially in temperature, although they may differ materially in quality or wetness. 80 These exhausted streams may then be mixed together without material thermodynamic disadvantage, and the combined stream may advantageously be conducted directly to the liquefying or rectifying apparatus without 85 being returned to the interchanger at all.

Now, a turbine, and particularly a turbine of the DeLaval type consisting of a relatively small wheel running at a relatively great speed, is particularly well 90 adapted for the purpose of expanding gases or, in this particular case, gaseous mixtures from the very high pressures under which they are put.

One of the chief advantages of this type 95 of expansion engine is that it is possible to combine in a single turbine wheel running in a single casing, several different expansion engines of the series contemplated in my said application.

In the drawing 2 represents a turbine 100 wheel running in a casing 3. From a plurality of points *a*, *b* and *c* pipes 4, 5 and 6 lead to the turbine structure and through these pipes a plurality of streams are discharged through suitable nozzles against the buckets of the turbine wheel.

The coldest engine represented in the drawing consists of a group of nozzles 7, the next warmer engine of a group of noz- 110

zles 8 and the remaining still warmer engine of nozzles 9, all having in common the same wheel 2.

The expanded fluids discharged from the 5 different nozzles, after imparting energy to the wheel, mingle indistinguishably in turbine exhaust passage 10.

It is obvious that as many expansion engines as may be desired can be combined in 10 this way on a single wheel, the rotation and friction losses of the machine being divided among the various engines of the series instead of being duplicated by the use of a plurality of separate engines as was heretofore the case.

Furthermore, a considerable increase in 20 the number of expansion engines associated with the colder portions of the interchanger can be made with very little decrease in the efficiency of each, due to its small output, and with comparatively little increase in the cost of construction of the apparatus.

It is thus possible to make a much more 25 complete adjustment of the effective heat capacity of the streams to be cooled remaining in the interchanger to equality with the effective heat capacity of the cooling streams, than would be commercially practicable with any form of construction that 30 involved a mechanically distinct structure for each expansion engine.

In the foregoing no attempt has been 35 made to show an actual turbine construction since this is a matter of common knowledge and the application of the invention is a matter of course.

It is obvious that a combination turbine 40 of this sort may well be designed with different nozzle-angles in the various groups of nozzles, or with different nozzle exit-heights, or with both, so that each expansion engine may have, individually, as high an efficiency as the conditions of the design permit.

45 I claim:

1. In combination with an interchanger, 50 a multiple turbine defining a plurality of separate expansion engines and means for feeding said engines from points of different temperature levels of the interchanger.

2. In combination with an interchanger, 55 a turbine and separate conduits for passing a plurality of streams at different temper-

atures from the interchanger to the turbine.

3. In combination with an interchanger, 60 a turbine and conduits for passing a plurality of streams from different levels along a passage of the interchanger to the turbine wheel to act on different parts thereof.

4. In combination with an interchanger, 65 a multiple turbine having a single wheel and different groups of nozzles defining separate expansion engines, and conduits for passing a plurality of streams from different temperature levels of the interchanger to the turbine, said conduits leading to separate nozzles or groups of nozzles for expanding the said streams to substantially the same pressure and for directing the 70 said streams against different portions of the turbine wheel.

5. The combination of an interchanger 75 having a passage for gas under considerable pressure, to be cooled in counter-current heat-exchanging relation with a cool fluid, a turbine constructed to define a plurality of separate expansion engines, and conduits for passing a plurality of streams from different levels of said passage to the said separate expansion engines to be separately expanded.

6. The combination of an interchanger 80 having a passage for gas under considerable pressure, to be cooled in counter-current heat-exchanging relation with a cool fluid, a turbine constructed to define a plurality of separate expansion engines having a common wheel, and conduits for passing a plurality of streams from different levels of 85 said passage to the said separate expansion engines to be separately expanded.

7. The combination of an interchanger 90 having a passage for gas under considerable pressure, to be cooled in counter-current heat-exchanging relation with a cool fluid, a turbine constructed to define a plurality of separate expansion engines having a common wheel and a common exhaust, and conduits for passing a plurality of streams 95 from different levels of said passage to the said separate expansion engines to be separately expanded.

In testimony whereof I affix my signature.

HARVEY N. DAVIS.
